DESIGN FOR A KEY FOR TUNING STRINGED INSTRUMENTS

James W. Bartlett, Schenectady, N. Y.

Application April 27, 1944, Serial No. 113,388

Term of patent 14 years

(Cl. D54—16)

To all whom it may concern:

Be it known that I, James W. Bartlett, a citizen of the United States and residing at Schenectady, in the county of Schenectady and State of New York, have invented a new, original, and ornamental Design for a Key for Tuning Stringed Instruments, of which the following is a specification, reference being had to the accompanying drawing, forming part thereof.

Fig. 1 is a perspective view of a key for tuning stringed instruments showing my new design; and

Fig. 2 is a sectional view on the line 2—2 of Fig. 1.

I claim:

The ornamental design for a key for tuning stringed instruments, as shown.

JAMES W. BARTLETT.
